UNITED STATES PATENT OFFICE

97,857

DESIGN FOR A RADIOCABINET

Joseph Macák, Chicago, Ill.

Application September 24, 1935, Serial No. 58,677

Term of patent 7 years

To all whom it may concern:

Be it known that I, Joseph Macák, a citizen of the United States of America, residing at Chicago, in the county of Cook and State of Illinois, have invented a new, original, and ornamental Design for a Radiocabinet, of which the following is a specification, reference being had to the accompanying drawing, forming part thereof.

Figure 1 is a front elevational view of the radio cabinet;

Figure 2 is a side elevational view; and

Figure 3 is a top plan view of the cabinet on a reduced scale, the projecting legs being omitted.

The front and rear sides of the cabinet are of similar design except for the control elements on the front wall. The side walls are of similar design.

I claim:

The ornamental design for a radiocabinet as shown and described.

JOSEPH MACÁK.
